(57) **CLAIM**

I claim the ornamental design for a bait station with sight
glass, as shown and described.

DESCRIPTION

FIG. 1 is a side elevation view of a bait station with sight
glass;

FIG. 2 is a front elevation view thereof;

FIG. 3 is a top plan view thereof;

FIG. 4 is a bottom plan view thereof;

FIG. 5 is an opposite side elevation view thereof; and,

FIG. 6 is a rear elevation view thereof.
